UNITED STATES PATENT OFFICE.

DAVID J. LUPTON, OF JERUSALEM, OHIO.

CAR-PLATFORM.

SPECIFICATION forming part of Letters Patent No. 433,295, dated July 29, 1890.

Application filed December 17, 1889. Serial No. 334,042. (No model.)

To all whom it may concern:

Be it known that I, DAVID J. LUPTON, of Jerusalem, in the county of Monroe and State of Ohio, have invented a new and Improved 5 Car-Platform, of which the following is a full, clear, and exact description.

My invention relates to platforms applied to railway, freight, and passenger cars; and the object of my invention is to provide a 10 platform that will entirely fill the space between the ends of the cars, so that no one can fall between them, and also to connect and attach the platform in such a manner that the rocking and jolting of the cars while in 15 motion will be greatly lessened.

To this end my invention consists in a platform pivoted to the top of the car-coupler, so that the ends of the platform may move backward and forward in recesses in the ends 20 of the car, and adapted to have its outer edge coupled to the platform of the adjoining car. This construction will be hereinafter fully described, and specifically pointed out in the claims.

25 I have shown my invention applied to a passenger-car where it will prevent passengers from falling between the ordinary platforms of the car; but it is especially applicable to freight-cars, where it will prevent 30 train-men from falling between the cars as they are at work upon the outside thereof.

Reference is to be had to the accompanying drawings, forming a part of this specification, in which similar letters of reference indicate 35 corresponding parts in all the figures.

Figure 1 is a front elevation of the platform as applied to an ordinary passenger-car. Fig. 2 is a plan view of the same with a portion of the passenger-platform broken away 40 to show the recess within it, and Fig. 3 is a vertical cross-section of the platform and coupler to which it is attached on the line x x of Fig. 2.

The platform A may be made either of 45 wood or metal. It is narrowed in the center and is pivotally attached to the top of the coupler B by the pin a . The sides or ends of the platform A are widened out on each side of the center at the part l , so as to project 50 back into the chambers C of the passenger-platform D. The ends of the platform A will thus have a good bearing upon the timbers E,

at the outer side of the chambers C, and be able to sustain any weight likely to come upon them.

The outer edge of the platform A is made straight, and is provided with a projecting lug b , attached to the upper and lower side thereof, so that when the platform is placed against the platform of an adjoining car the straight edges of the two platforms will come together and be clasped by the lugs b b , which will prevent them from breaking down in the center.

When the cars bump together, the platforms 65 A between the cars will yield with the buffer-spring of the coupler to which they are attached, and as the cars rock and shake, especially as they round a curve, the motion will be greatly lessened by the platforms, as 70 they will bear solidly together and swivel on the pivot a .

The platform A should be perforated to allow the coupler-rod d to pass up through it.

I have shown the platform A attached to 75 a coupler B, for which I am about to apply for Letters Patent; but I have not described the coupler, as it forms no part of my invention.

When the platform A is applied to a freight- 80 car, the end beams of the car should be recessed in the same manner as the passenger-platform D in the drawings, so as to afford room for the widened ends of the platform.

Having thus described my invention, I 85 claim as new and desire to secure by Letters Patent—

1. The combination, with a railway-car having recesses C in the ends thereof, of the platform A, pivotally attached to the car-coupler 90 B, and having widened ends l , projecting into the recesses C, substantially as shown, and for the purpose described.

2. The combination, with a railway-car, of a movable platform pivotally attached to the 95 car-coupler, said platform having widened ends projecting into recesses in the end of the car, and having its outer edge provided with lugs adapted to clasp the edge of an adjoining platform, substantially as described. 100

DAVID J. LUPTON.
